PIN WHEEL FEEDING UNIT

Albert W. Metzner, Dayton, Ohio, assignor to The Standard Register Company, Dayton, Ohio, a corporation of Ohio

Application January 12, 1950, Serial No. 138,233

16 Claims. (Cl. 74—243)

I

This invention relates to pin type strip feeding devices, and more particularly to a retractible pin type strip feeding device in which the individual feeding pins are simultaneously withdrawn or retracted within the periphery of the feeding device.

Positive pin type strip feeding devices embodying a plurality of pin wheels are now commonly used and generally well known. There are two common types of pin wheel employed, one having reciprocating pins and the other having fixed pins. In the first type, the pins are progressively projected from within the periphery of the wheel as it passes during its rotation a specified point. In the second type, the pins are fixed relative to the wheel, being in effect a solid integral part thereof and projecting from the periphery of the wheel throughout its entire periphery.

The present invention is related in a general way to this second type of pin wheel, but provides a resilient mounting for the individual pins, movement of which mounting simultaneously retracts all of the pins within the periphery of the pin wheel, or simultaneously projects all of the pins therefrom. During certain periods of use of such positive pin type strip feeding devices it is desirable to retract all of the pins within the periphery of the feeding device where they will be concealed and out of the way. Heretofore all applications requiring periodic movement of the feeding pins to inoperative position necessitated the reciprocating type of pin wheel.

The present invention provides a positive pin type feeding device incorporating not only all of the advantages of a fixed pin type of feeding device, but all the further advantage of a construction permitting the complete retraction of all the pins within the surface of the feeding device when such withdrawal or retraction is desired in connection with the particular use to which the strip feeding device is put.

The object of the present invention is to simplify the construction as well as the means and mode of operation of a pin type feeding device as disclosed herein, whereby such devices may not only be economically manufactured but will be more efficient and satisfactory in use, adaptable to a wide variety of applications, having relatively few parts and be unlikely to get out of repair.

A further object of the invention is to provide a pin type feeding device in which the pins are both movable and resiliently mounted so that they may be either extended or retracted relative to the surface of the feeding device.

2

A further object of the invention is to provide in a pin type feeding device of the character described, a simple and efficient means of simultaneously adjusting all of the individual pins from operative to inoperative position and vice versa.

A further object of the invention is to provide an individual resilient oscillatory mounting for the individual pins.

A further object of the invention is to provide an oscillatory control member for the individual resilient mountings for simultaneously adjusting the individual pins relative to the periphery of the strip feeding device.

A further object of the invention is to provide a pin type feeding device possessing the advantageous structural features, the inherent meritorious characteristics and the mode of operation herein mentioned.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

Referring to the accompanying drawing, wherein is found the preferred but obviously not necessarily the only form of embodiment of the invention,

Fig. 1 is a front view of an assembly pin type strip feeding device embodying the present invention;

Fig. 2 is a side view thereof, looking toward the right of Fig. 1;

Fig. 3 is a side view thereof, looking toward the left of Fig. 1;

Fig. 4 is a sectional view taken substantially on line 4—4 of Fig. 3;

Fig. 5 is a view similar to Fig. 3, but with portions broken away, showing the pins in operative position;

Fig. 6 is similar to Fig. 5, showing the pins in inoperative position;

Fig. 7 is a detail view showing the inside of the adjusting knob; and

Fig. 8 is a detail perspective view of the resilient pin supporting wire.

Like parts are indicated by similar characters of reference throughout the several views.

Referring to the drawing, there is shown in Fig. 1 an assembled strip feeding device embodying the present invention. In this form, the feeding device comprising a pin carrying body 1 is secured to a rotary supporting shaft 2 for unison

rotation therewith by a key 3 having a press fit within the body 1 and engageable within an aligned complementary keyway within the periphery of the shaft 2. The body 1 is mounted for longitudinal sliding motion upon the shaft 2, it being retained in adjusted position thereon by means of a latch 4, pivotally mounted to the body at 5 for removable engagement within a selected notch 6 on the side of the supporting shaft 2.

A series of individual feeding pins 7 are slidably carried within individual grooves 8 arranged in radially spaced relation about the main body 1. As shown in Figs. 5 and 6, the pins 7 are mounted for radial reciprocatory movement into and out of the supporting body 1. When extended from the periphery of the body 1, the pins 7 engage spaced perforations in a record strip 9 to advance the strip in unison with the rotation of the strip feeding device. When the pins are withdrawn as in Fig. 6, the strip may be advanced by other feeding means.

The pins 7 are retracted and expelled relative to the body 1 by rotary adjustment of a control knob 10 supported by the body 1 intermediate a centrally extending hub portion 11 of the body and a peripheral flange 12 thereof. The knob 10 is maintained in position relative to the body 1 by means of a nut 13, recessed within the knob and having threaded engagement with the end of hub portion 11.

Concentrically arranged upon the inner surface of the knob 10 is a series of holes 14 (Fig. 7) through which extend ends 15 of flexible resilient mounting wires 16. The opposite ends 17 of the wires 16 are seated within the ends of the individual pins 7 in axial alignment therewith. The mounting wires are free to oscillate within the holes 14 upon rotation of the control knob 10.

Referring to Fig. 5, counterclockwise rotation of knob 10 from the position shown therein to the position shown in Fig. 6 retracts the resilient wires 16 and with them the individual feeding pins 7, the wires 16 being in effect wound about the hub 11 in a tight spiral. Such movement of the support wires is permitted by freely mounting the wires 16 in the retaining holes 14 for limited oscillatory motion. Upon rotation of the control knob 10 in a clockwise direction, the resilient wires are immediately expanded, thereby pushing the pins 7 outwardly or upwardly relative to the periphery of the body 1.

To locate the control knob 10 in either of its adjusted positions, there is provided in the extending flange 12 a pair of indexing holes 18 and 19, representing respectively operative (extended) position and inoperative (retracted) position of the pins 7. Cooperating with the indexing holes 18 and 19 is a spring biased plunger 20 carried by control knob 10 so as to normally project from the periphery thereof. Movement of the plunger 20 is controlled by a projecting finger operated stud 21 extending through an elongated guide slot 22 adjacent the periphery of the control knob 10. Upon depression of the stud 21, the plunger 20 is withdrawn from either indexing hole 18 or 19, whereupon control knob 10 is free for rotative movement relative to the body 1 to either extend or retract the feeding pins 7.

Control knob 10 is removable from the unit for servicing and the like by removal of the nut 13. A pair of recesses 23 are provided in the outer surface of the nut for engagement of a spanner wrench therewith to facilitate such removal. Upon withdrawal of control knob 10, however, the inherent resiliency of the pin supporting

wires 16 results in immediate disarrangement thereof upon being freed of the restraint imposed by the knob 10 and its retaining holes 14. To prevent such disarrangement and facilitate the reassembly of the unit, an auxiliary anchoring ring 24 is passed over the ends 15 of the support wires 16, thereby maintaining the wires in proper spaced relation for engagement by the knob 10. Such auxiliary anchor ring is supported by the wires and is positioned immediately adjacent the inner face of control knob 10 in contacting relation therewith when the unit is assembled. See Fig. 4.

The present structure presents a relatively simple, but nonetheless efficient and satisfactory means of resiliently and individually mounting a series of feeding pins for simultaneous movement either into or out of the periphery of a pin supporting body. For other means of achieving a substantially similar result by use of another structure, reference is made to copending application Serial No. 138,226, filed of even date here-with.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A pin type strip feeding device for progressively advancing a continuous strip of material having feeding configurations therein past a given point, including a rotary shaft, a circular body mounted thereon for unison rotation therewith, means for adjusting the body longitudinally of the shaft and maintaining it in adjusted position, a plurality of radially spaced recesses arranged about the periphery of the body and extending inwardly therefrom, a plurality of individual reciprocatory feeding pins movably supported in said recesses, a rotary hub supported within said body for limited rotary motion relative thereto, locking means carried thereby and engageable with the body to define the opposite limits of rotation relative to the body, a plurality of individual resilient supporting members interconnecting the rotary hub and the individual feeding pins upon which members the pins are resiliently supported relative to the body, and means for reciprocating said pins relative to the body comprising a rotatable connection between the hub and each of the individual supporting members, the construction and arrangement being such that upon rotation of the hub in one direction the resilient supporting members are simultaneously retracted relative to the hub to thereby simultaneously retract the feeding pins within the periphery of the body and upon rotation of the hub in the opposite direction the resilient supporting members are simultaneously extended relative to the hub to thereby project the feeding pins relative to the body.

2. A pin type strip feeding device for progres-

sively advancing a punched continuous strip of material past a given point, including a rotary body, a rotary supporting shaft therefor, a plurality of strip engaging pins carried by said body in circumferentially spaced relation and movably mounted therein for reciprocatory motion into and out of said body, individual resilient supporting members for each pin, a rotary hub within said body with which said supporting members are engaged for limited oscillatory motion relative thereto, the construction and arrangement being such that rotary motion of the hub causes the strip engaging pins to be simultaneously retracted or extended relative to the periphery of the body.

3. A pin type strip feeding device for progressively advancing a punched continuous strip of material past a given point, including a rotary body, a plurality of movable strip engaging pins individually supported therein at circumferentially spaced intervals, and means for moving said pins radially of the body, including a movable hub mounted for limited oscillatory motion relative to said body, a plurality of resilient pin supporting members interconnecting the individual feeding pins with said hub, said supporting members being pivotally interconnected with said hub, the construction and arrangement being such that upon oscillation of said hub in opposite directions relative to said body the plurality of strip engaging pins are simultaneously withdrawn and projected relative to the periphery of the body.

4. A pin type strip feeding device for progressively advancing a punched continuous strip of material past a given point, including a rotary body, a plurality of individual strip engaging pins movably mounted therein at circumferentially spaced intervals, a rotary hub mounted in concentric relation with said body for unison rotation therewith, means for rotating said hub relative to said body a predetermined distance, individual members interconnecting said hub and said pins upon which said pins are supported, said members being positioned in substantially tangential relation to said hub at one limit of adjustment to project said pins outwardly relative to said body and positioned in substantially concentric relation to said hub at the opposite limit of adjustment to retract said pins inwardly relative to said body.

5. A pin type strip feeding device for progressively advancing a punched continuous strip of material past a given point, including a rotary body, a plurality of individual strip engaging pins movably mounted therein at circumferentially spaced intervals, individual resilient supporting members enclosed within said body upon which each of said pins is individually supported, and means for simultaneously angularly displacing said members a predetermined extent relative to said body, the pins supported thereby being withdrawn within said body at one limit of displacement, and projected outwardly from said body at the opposite limit of displacement.

6. A pin type strip feeding device for progressively advancing a continuous strip of punched material past a predetermined point, including a body, a plurality of individual strip feeding pins mounted therein for reciprocatory motion relative thereto, an oscillatory control member common to said plurality of individual pins for simultaneously retracting all of said pins within said body or projecting said pins exteriorly of said body, a resilient individual and independent

connection between said control member and each of said pins, and means for oscillating said control member to alternate predetermined positions of adjustment relative to said body corresponding to the retracted and projected pin positions.

7. A pin type strip feeding device for progressively advancing a continuous strip of material past a predetermined point, including a plurality of strip feeding pins, a common mounting therefor relative to which the pins are capable of reciprocatory motion, a control member common to said plurality of pins and movable relative to the mounting movement of said control member in one direction simultaneously withdrawing all of said pins within said body and movement of said control member in the opposite direction simultaneously projecting all of said pins outwardly relative to the surface of said body, and a resilient individual and independent connection between said control member and each of said pins effecting the described withdrawing and projecting movements of said pins in response to movements of said control member.

8. A pin type strip feeding device for progressively advancing a continuous strip of record material past a predetermined point, including a plurality of reciprocating feeding pins, a mounting body common thereto in which said pins are mounted for reciprocatory motion relative to the surface thereof, a control member supported within said body for limited motion relative thereto, and a plurality of movable resilient mounting members, one for each feeding pin, upon one end of which the feeding pin is supported, the other end of which is movably supported within the control member, the construction and arrangement being such that the mounting members are simultaneously moved by the control member to thereby reciprocate said pins relative to the mounting body.

9. A pin type strip feeding device for progressively advancing a continuous strip of record material past a predetermined point, including a plurality of movably mounted feeding pins, a common mounting therefor relative to which the pins are movable, a control member carried by said mounting and capable of limited movement relative thereto, and movable resilient pin supporting means carried by said control member for simultaneous movement therewith to move said pins relative to said mounting.

10. A pin type strip feeding device for progressively advancing a continuous strip of record material past a predetermined point, including a plurality of movably mounted feeding pins, a common mounting therefor relative to which the pins are movable, a control member carried by said mounting and capable of limited movement relative thereto, a plurality of movable resilient pin supporting members each supporting an individual pin, and means for interconnecting said movable pin supporting members with said control member for synchronous movement therewith to thereby move said pins relative to said mounting.

11. A pin type strip feeding device wherein a series of feeding pins are adjustably mounted for simultaneous movement into and out of feeding position, including a pin supporting body, a plurality of pins adjustably supported therein, a plurality of duofunctional resilient pin supporting and pin adjusting members, and an actuator therefor common to and connected to all of said duofunctional members, movement of said ac-

tuator causing simultaneous movement of said feeding pins into and out of feeding position.

12. A pin type feeding device for progressively advancing a continuous strip of material past a given point, including a plurality of simultaneously movable pins, a mounting body within which the pins are supported for simultaneous movement relative thereto, individual resilient supporting members for each pin mounted within said body, and an actuator therefor common to and connected to all of the supporting members, operation of which simultaneously projects or retracts said pins relative to the mounting body.

13. A pin type feeding device for progressively advancing a continuous strip of material past a given point, including a plurality of adjustable feeding pins, a supporting member upon which said pins are adjustably supported, and means for simultaneously adjusting said pins from operative to inoperative position and vice versa, including an actuator common to said pins and adjustably carried by the supporting member for limited adjustment relative thereto and an independent resilient member extending between said actuator and each of said pins, each of said members being connected at its one end to said actuator and at its opposite end to a respective one of said pins.

14. A pin type feeding device, including a wheel having a peripheral series of relatively closely spaced apart radial openings, feeding pins slidably mounted in said openings, a control knob in concentric adjacent relationship to said wheel, and having a series of holes in concentric relation to the axis thereof, supporting members for said feeding pins having their one ends respectively pivotally received in said holes and having body portions extending substantially at right angles to said one ends and in spiral overlapping relation with the body portions of adjacent supporting members, the opposite ends of said members being connected to the inner ends of respective

feeding pins, and means for securing said control knob to said wheel in alternative positions of relative rotary adjustment in one of which said feeding pins are extended relatively to the periphery of the wheel and in the other of which said pins are retracted.

15. A pin type feeding device, including a wheel having a peripheral laterally projecting flange and a series of relatively closely spaced apart through radial openings in said flange, a common supporting member in side-by-side relatively fixed relation to said wheel and having a wall in spaced parallel relation to the axes of said radial openings, a circular series of longitudinal openings in said wall concentric with and inside the plane of the flange on said wheel, individual supporting members for each said feeding pins including a wire having one end received in a respective longitudinal opening in said wall and projecting longitudinally substantially into the plane of said feeding pins, each said wires further having an outwardly curved body portion and an outer or opposite end connected to a respective one of said feeding pins, the several wires extending in spiral overlapping formation in their body portions and being resilient whereby to impart a yielding axial thrust to the feeding pins in a radially outward direction.

16. A pin type feeding device according to claim 15, characterized in that said common supporting member is adjustable in a rotative sense relatively to said wheel whereby to retract and to extend said feeding pins with respect to the flange of said wheel.

ALBERT W. METZNER.
